UNITED STATES PATENT OFFICE

156,176

DESIGN FOR AN APPLIQUE OR THE LIKE

Morris Silberman, New York, N. Y., assignor to Moses Streesover, New York, N. Y.

Application December 13, 1947, Serial No. 143,132

Term of patent 3½ years

(Cl. D3—9)

To all whom it may concern:

Be it known that I, Morris Silberman, a citizen of the United States of America, residing in the city of New York, county of Kings, and State of New York, have invented a new, original, and ornamental Design for an Applique or the like, of which the following is a specification, reference being had to the accompanying drawing, forming part thereof, wherein:

The figure is a plan view of an applique showing my new design.

The essential features of the design are shown in full lines.

I claim:

The ornamental design for an applique or the like, substantially as shown and described.

MORRIS SILBERMAN.
